(57) **CLAIM**

The ornamental design for a hood for a barbecue grill, as shown and described.

DESCRIPTION

FIG. 1 is a top right perspective view of a hood for a barbecue grill showing my new design;

FIG. 2 is a top right perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The barbecue grill base, handle, and thermometer face shown in broken lines in FIG. 1 is for illustrative purposes only and forms no part of the claimed design.
